Fig. 3.

Fig. 4

Fig. 5

To all whom it may concern:

Be it known that I, Melvin H. Boldt, a citizen of the United States, residing at Glenview, in the county of Cook and State of Illinois, have invented a new, original, and ornamental Design for an Electric Skillet, of which the following is a specification, reference being had to the accompanying drawings, forming a part thereof.

In the drawings:

Figure 1 is a top plan view of an electric skillet showing my new design;

Figure 2 is a front elevational view thereof;

Figure 3 is a side elevational view thereof as viewed from the left hand side of Figure 1;

Figure 4 is a side elevational view thereof as viewed from the right hand side of Figure 1; and

Figure 5 is a bottom plan view thereof.

I claim:

The ornamental design for an electric skillet, substantially as shown.
